UNITED STATES PATENT OFFICE

109,105

DESIGN FOR A TABLECLOTH OR SIMILAR ARTICLE

Joseph Rosenfield, New York, N. Y.

Application March 5, 1938, Serial No. 75,606

Term of patent 3½ years

To all whom it may concern:

Be it known that I, Joseph Rosenfield, a citizen of the United States of America, residing in New York city, in the Borough of Manhattan, county and State of New York, have invented a new, original, and ornamental Design for a Tablecloth or Similar Article, of which the following is a specification, reference being had to the accompanying drawing, forming part thereof, wherein the figure is a plan view of a tablecloth or similar article, showing my new design.

I claim:

The ornamental design for a tablecloth or similar article, substantially as shown.

JOSEPH ROSENFIELD.
